UNITED STATES PATENT OFFICE.

JESSE ALEXANDER, OF BROOKLYN, NEW YORK, ASSIGNOR, BY MESNE ASSIGNMENTS, TO LEE ALEXANDER, KITTIE ALEXANDER, JR., JESSE ALEXANDER, JR., AND TYVE ALEXANDER.

TYPE-WRITER PAPER-FEEDING MECHANISM.

No. 833,285.

Specification of Letters Patent.

Patented Oct. 16, 1906.

Original application filed June 2, 1902, Serial No. 109,925. Divided and this application filed March 9, 1903. Serial No. 146,900.

To all whom it may concern:

Be it known that I, JESSE ALEXANDER, a citizen of the United States, residing at Brooklyn, in the county of Kings, State of New York, have invented certain new and useful Improvements in Type-Writer Paper-Feeding Mechanism, of which the following is a full, clear, and exact description.

My invention relates to improvements in type-writers, and particularly to the mechanism for feeding the paper about the platen in that class having a revoluble platen.

This is a divisional application from the application filed by me June 2, 1902, serially numbered 109,925.

The object of this invention is to effect a proper feeding of the paper about the platen or roller and to provide a means for releasing the pressure of the guides upon the platen by a simple movement. I also provide a means for adjusting the pressure of certain of the guiding-rollers.

It is also my object to provide an introductory guide which may be removably attached to the general carriage structure and make the structure compact.

The invention consists in the structure and arrangement of an introductory guide, a shield or lower guide, and of the presser-rollers and the general location and construction of the parts, as will more fully appear on an examination of the following specification and the accompanying drawings.

Figure 1 is a plan view of those parts of the type-writer carriage and guides which embody my invention. Fig. 2 is a plan view of the presser-rollers and the releasing and adjusting mechanism therefor. Fig. 3 is a cross-section and end elevation of the parts of a carriage structure embodying my invention. Fig. 4 is a rear view of the introductory guide, the central part being broken away.

1 is the introductory guide by means of which the paper is first led to the rear of the platen 2.

3 is the lower guide or shield, which is secured to the bar 4 and extends downward and forward around the front of the platen 50 and terminates at the front in a scale-bar 12.

5 are screws for attaching the introductory guide 1 to the bar 4. The connection is made by means of the posts 6, which are

slotted at the lower ends, as shown particularly in Fig. 4. The introductory guide may therefore be readily attached to or detached from the bar 4 and the other parts of the carriage structure to be described by simply adjusting the screws 5.

7 are side plates which constitute part of the carriage structure and in which the bar 4 finds its support. 8 is a platen-shaft, which has bearings in these plates 7 and is provided with the handles or knobs 9.

10 is one of the rear presser-rollers which are provided, three in number. Obviously the roller might be made a continuous one from end to end, but it is preferred to form it in sections.

11 are front presser-rollers which are provided to act in a manner similar to the rear rollers 10 for the purpose of holding the paper in close contact with the platen.

101 is a rod which is carried by the side plates 7 and carries the arms 100 and 110, by means of which the rollers 10 and 11 receive their support.

102 is a shaft on which the rollers 10 are mounted. The arms 100 are preferably slotted to receive the ends of the shaft 102, so that when the arms are retracted the shaft 102 may be removed, together with the rollers 10, if desired.

The rollers 10 and 11 are pressed toward the platen 2 by means of a helical spring, which is preferably formed in two sections 112 and 113, connected together by means of the ratchet 114. The pressure which these rollers 10 and 11 exert against the platen may be readily adjusted by simply turning the ratchets 114 to either increase or decrease the torsional effect of the springs 112 113.

150 is a lever which extends upward, so as to be readily reached. This is connected to the shaft 15, which is pivoted in the side plate 7 of the carriage. 105 are arms carried by this shaft 15, which may extend forward and, being slotted at the end, thus engage the ends of the shaft 102. Pressure upon the lever 150 will rock the shaft 15, and thus retract or release the rollers 10 from their pressure against the platen, so that the paper may be adjusted as desired.

13 are spring-finger guides which are provided at the front of the platen for holding the paper securely at the edges. These

guides are preferably slidably mounted upon the auxiliary platen and shifting rod 131, which is carried by the side plates 77, the lower ends of the fingers being bent up to 5 surround the rod.

14 is an auxiliary guide in the form of an inverted frame, the ends of which may be slipped into recesses in the bar 140, which is a part of the stationary frame of the machine—

- 10 for instance, the type-bar plate. This frame 14 is preferably formed of spring metal, so as to be held in place by virtue of its own tension. 141 is a roller carried by this frame 14 for the purpose of assisting in guiding the 15 paper at or near the central portion. This guide being supported by the machine forms a means for holding back the paper near the printing position, so that it shall lie out of the way of the printing-type, which are 20 adapted to operate on a horizontal line visible to the operator.

What I claim is—

- 1. In a type-writing machine, a carriage-frame, a platen carried thereby, a rod carried 25 by said frame at the rear of said platen, a paper-guide shield secured at the rear to said rod and extending downward and upward around the lower side of the platen, a scale carried by the front edge of said shield, 30 screws threaded into said rod, and a paper-introducing guide removably secured to said rod by said screws.

- 2. A type-writer-carriage construction including side frames, a platen mounted there- 35 in, a rod carried by said frames at the rear of said platen, a shield attached to said rod and extending underneath and in front of said platen, an introductory paper-guide comprising a curved member extending between 40 the side frames and at the rear of the platen,

a pair of supporting-posts connected to said member and having their lower ends slotted and screws for securing the posts to said rod.

3. In a type-writing machine, a carriage-frame, a revoluble platen carried thereby, 45 spring-pressed rollers operating to press against said platen, and means for retracting some of said rollers comprising a shaft pivoted in the side frames of said carriage having a lever rigidly secured at one end adapted to be engaged by the finger, and a slotted arm engaging the shaft upon which said rollers are mounted.

4. A type-writer-carriage construction including side frames, a platen mounted there- 55 in, a rod carried by the side frames and beneath the platen, a spring-pressed shaft at the rear of said platen pivoted on said rod, pressure-rollers mounted on said shaft, a second shaft pivoted in carriage side frames, a 60 slotted arm secured to said second shaft engaging the roller-carrying shaft and a lever secured to said second shaft adapted to be engaged by the finger for retracting said rollers. 65

5. A type-writer-carriage construction including side frames, a platen mounted there- 70 in, a rod mounted beneath said platen, a pair of spring-pressed arms pivotally carried by said rod and slotted in the ends, a pressure-roller-carrying shaft having its ends resting in said slots in said arms, a retracting-shaft pivoted in said frames and having an arm with a slotted portion engaging the roller-carrying shaft and an operating-lever carried 75 by said retracting-shaft.

JESSE ALEXANDER.
